CLAIM

The ornamental design for a charging cradle for a skin care device, as shown and described.

DESCRIPTION

1. Charging cradle for skin care device

1.1 : Perspective

1.2 : Front

1.3 : Back

1.4 : Left

1.5 : Right

1.6 : Top

1.7 : Bottom

1.8 : Bottom perspective view

The broken lines depict portions of the charging cradle for a skin care device that form no part of the claimed design.

1 Claim, 8 Drawing Sheets
